UNITED STATES PATENT OFFICE.

HARRY O. GRIZZELLE, OF NEW YORK, N. Y.

SAFETY TRUNK AND BAG CARRIER FOR AUTOMOBILES.

Application filed February 28, 1920. Serial No. 361,288.

To all whom it may concern:

Be it known that HARRY O. GRIZZELLE, a citizen of the United States of America, residing at New York, in the county of New York and State of New York, has invented new and useful Improvements in Safety Trunk and Bag Carriers for Automobiles, of which the following is a specification.

The object of the invention is to provide a simple, relatively inexpensive and efficient attachment applicable to the running boards of automobiles and similar vehicles for extension when required to receive and safely carry receptacles and packages including trunks, traveling bags and the like, and capable of folding into compact form when not in use so as to occupy an inconspicuous position on the vehicle without interfering with the normal use of the running board as a step, and with these objects in view the invention consists in a construction and combination of parts of which a preferred embodiment is shown in the accompanying drawings, wherein:

Figure 1 is a plan view of the carrier applied in the operative position to a vehicle. Figure 2 is a side view of the same in its folded position.

Figure 3 is a side view of the carrier extended and in operative position.

Figure 4 is an end view partly in section of the same.

Figure 5 is a detail section showing means for mounting and securing the carrier on the running board of the vehicle.

Figure 6 is a detail view in perspective showing one of the joints between corresponding lazy tongs units at the meeting edges of two adjoining walls of the structure.

Figure 7 is a detail view in perspective of the means whereby the lowermost unit of the side wall is mounted upon the base.

The device consists essentially of a three-sided receptacle having an outer side wall 10 and front and rear end walls 11 and 12 constructed respectively of lazy tongs with the extremities of the members 10^a of the side wall provided with inwardly extending ears 10^b upon which are pivotally mounted the adjacent extremities of the members of the end wall fillers, the inner extremities of the latter being connected by the elements 13 of folding corner uprights which rest at their lower ends upon the running board or step 14. The carrier also includes a base or

bottom 15 slidably mounted upon the running board or step by having its end edges engaged by clips 16 secured to the latter, and in order to provide for the inward and outward sliding movement of the base or bottom 15 to vary the depth or distance between the outer wall 10 and the plane of the uprights 13, or the side of the car as indicated at 17, the members 11^a of the end wall lazy tongs are extensible and comprise relatively movable elements 11^b and 11^c of which one is longitudinally slotted as shown at 18 to receive guide pins 19 on the other element.

Therefore not only is the receptacle extensible vertically by the relative pivotal movements of the members of the lazy tongs constituting the side and end walls, but the side wall is movable toward and from the plane of the corner uprights 13 to vary the dimensions of the receptacle in width by the extension longitudinally of the members of the end wall lazy tongs.

When collapsed the members of the end wall lazy tongs are reduced in length or in effect telescoped by the inward sliding movement of the bottom or base 15, and the members of both the side and end walls are folded into substantial parallelism adjacent to the plane of the running board or step 14 or equivalent supporting means.

The receptacle is fitted with a cap or cover 20 preferably consisting of the relatively adjustable members 20^a and 20^b flanged as at 21, whereby said cap or cover is adapted to be folded by relative movement of its members when the side wall is adjusted inwardly, and when the receptacle is folded, the cap or cover serves in connection with the base or bottom to form a housing in which the members of the lazy tongs are enclosed to present an appearance indicated in Figure 2.

The cap or cover is preferably provided with a grip or handle 22 to facilitate the extension of the device and connected with the end walls adjacent to their inner edges are hooks 23 or similar fastening means for engagement with keepers 24 which may be conveniently attached to the side of the vehicle to hold the receptacle in its extended and operative position. As will be understood particularly by reference to Figure 6 the adjoining walls of the structure, as for example a side wall and an end wall at their meeting edges, said walls being disposed in substantially perpendicular planes to form an

angle or corner of the receptacle, do not depend upon an upright or other frame element or member, but on the other hand the side joints of the units of the adjoining walls 5 are pivotally connected together at the angle as by providing an element such as 10^a of a unit of one wall with a terminal offset or angularly disposed ear 10^b upon which are pivotally mounted the extremities of the ele- 10 ments of the corresponding unit of the adjoining angularly disposed wall. The term "lazy tongs" as applied to the construction of the walls of the receptacle is employed in lieu of a more appropriate term to define a 15 structure consisting of a plurality of units each of which comprises intersecting elements disposed in pivotal relation at an intermediate point or subject to relative pivotal movement around a common intermediate point, the adjacent terminals of the elements or levers of the several units being pivotally connected together, and whereas in practice a pivot may be arranged to connect the elements of each unit at the intersection 20 or pivotal point, as in the ordinary form of lazy tongs constructions, it is wholly unnecessary to use such pivots in the present structure, owing to the fact that the elements of each unit will have the required relative 25 pivotal movement whether or not such pivots are used. In the end wall constructions pivots are shown at the pivotal points of the elements because of the additional extension characteristic of the elements to permit of a 30 longitudinal collapsing movement thereof to vary the depth from front to rear or from outer to inner wall of the receptacle in accordance with the inward and outward sliding movement of the base 15 to which the terminals of the elements on the lowermost unit 35 are attached by means of pins 25 operating in slots 26 in suitable blocks 27.

It will be obvious that the device when folded may occupy a position on the running board or step of the vehicle under such 40 conditions as not to interfere with the normal use thereof in entering and leaving the car, and when extended, such receptacles as trunks, traveling bags and the like may be 45 arranged therein and held in position for transportation without occupying space within the car and thus without interfering with the comfort of the occupants thereof.

What is claimed is:

55. 1. A collapsible trunk and bag carrier for vehicles having side and end walls con-

sisting of lazy tongs with the side joints of the units of adjoining walls pivotally connected at the angle, and a base upon which the terminals of the elements of the lowermost unit of the lazy tongs of one wall are slidably mounted. 60

2. A collapsible trunk and bag carrier for vehicles having side and end walls consisting of lazy tongs with the side joints of the units of adjoining walls pivotally connected at the angle, and a base having slotted bearing blocks, and the terminals of the elements of the lowermost unit of one of said walls being provided with pins for 65 sliding engagement with the slots of said bearing blocks. 70

3. A collapsible trunk and bag carrier for vehicles having side and end walls consisting of lazy tongs with the elements of the unit of one wall provided with terminal ears to which are pivoted the terminals of the elements of the corresponding units of the adjoining wall, the elements of the units of opposite walls being of telescoping construction. 75

4. A collapsible trunk and bag carrier for vehicles having side and end walls consisting of lazy tongs with the elements of the unit of one wall provided with terminal ears to which are pivoted the terminals of the elements of the corresponding units of the adjoining wall, the elements of the units of opposite walls consisting of relatively 80 slidable members. 85

5. A collapsible carrier for vehicles having a base or bottom and means for slidably mounting the same upon the running board or step of a vehicle, side and end walls consisting of lazy tongs, the side wall being carried by said base or bottom, and the outer extremities of the members of the end wall lazy tongs being connected with the members of the side wall lazy tongs, the inner extremities of the members of the end wall lazy tongs being connected by jointed inner uprights, and the elements of the end wall lazy tongs being relatively of extensible construction, an extensible cap or cover connected with the uppermost members of the 90 side and end wall structures, and means for locking the walls in their extended positions. 100

In testimony whereof he affixes his signature.

HARRY O. GRIZZELLE.
